JOHN N. LEONARD, OF ROCKVILLE, CONNECTICUT.

Letters Patent No. 92,619, dated July 13, 1869.

IMPROVED APPARATUS FOR DISPLAYING SPOOLS OF SILK, COTTON, &c.

The Schedule referred to in these Letters Patent and making part of the same.

To all whom it may concern:

Be it known that I, JOHN N. LEONARD, of the village of Rockville, county of Tolland, and State of Connecticut, have invented a new and useful Apparatus for Properly Displaying such Articles of Merchandise as Spool Sewing-Silk, Machine-Twist, Cotton-Threads, &c.; and I do hereby declare that the following is a full and exact description of the same, reference being had to the accompanying drawings, and to the letters of reference marked thereon.

Figure 1 represents a vertical section;

Figure 2 is an outline view of the entire apparatus;

Figure 3 is a section through the line *z z*;

Figure 4 is a section of column A, through line *x x*; and

Figures 5 and 6 are outline views of the label.

Excepting by the use of glass show-cases (which are not only injurious to colors by almost constant exposition to light, but glass is itself an absorbent of colors,) the only means by which the merchant or salesman can ostend or display to customers and purchasers his spool-silk, threads, &c., is to take from the shelf and open numerous boxes and packages, and this often to effect very small or no sales.

As fine colors soon become faded when too constantly exposed to rays of natural light, any mechanical arrangement to assist the salesman in displaying such goods must be so constructed as to open only at such times as actually required for the purpose, and closed at all other times, to shield them from the action of the elements.

This is an instrument for displaying colors; and is so arranged that a great number of spools of silk or thread of various colors and shades may be brought to the point of observation without the slightest difficulty, and with the same facility closed from sight and exposure to atmospheric circulation, as will be seen by the following description of its construction.

Construction.

Alternately connected, by spur-wheels C C, are the bottom journals of A A, which are reed-like columns, hollow in the centre, to admit of numerous spools, and provided at the top with journals, which, extending into the cover D, form a proper support thereto.

In connection with spur-wheels C C, by means of intermediate wheels E E, there is another wheel, F,

which is made fast to the bottom of G, a column extending to and through i, the cover D, and provided there with a lever or hand-wheel, L.

At the bottom of base, B, there is a circular groove, which corresponds with a similar groove at the base of J, and between these two grooves, at proper intervals, are placed three round balls or spheres, H, of uniform size, on which rests the entire apparatus above the base, B, affording a very simple means for its rotation.

The spools are held fast in the columns by means of wire rods, M, supported by shelves K, which are as numerous as the styles or colors desired to be shown in each column.

As it would deface the ordinary labels of spools to slip them over wire rods, my labels, O, to overcome this, are provided with a hole, N, ornamentally perforated through them, leaving ample margin for the necessary letters and figures.

The shelves K may be used without the rods M, if the ordinary labels are preferred. However, with or without wire rods, the spools are placed within the hollow columns, and the following is the mode of operation:

By means of the hand-wheel, all of the columns containing spools may be made to revolve and display all the goods thereon; and in case the desired color does not appear on the side toward the observer, the whole upper portion of the apparatus may be revolved upon the main base, and by the same means the said columns are revolved so as to bring the face of the spools toward the centre column, shielding them from destructive agents.

The object of revolving the hollow columns alternately is to secure a tight and frictionless joint between them.

Claim.

What I claim as my invention, and desire to secure by Letters Patent of the United States, is—

The combination of hollow columns A A with spur-wheels C C, with the revolving base B, cap D, column G, and base J, all as described.

J. N. LEONARD.
